EVAPORATOR WICK

Milton A. Powers and Robert C. Champlin, Detroit,
Mich., assignors to Skuttle Manufacturing Company,
Milford, Mich., a corporation of Michigan

Application June 17, 1954, Serial No. 31,033

Term of patent 14 years

(Cl. D16—2)

FIG. 3

FIG. 1

FIG. 4

Figure 1 is a front elevation of an evaporator wick showing our new design;

Figure 2 is a top view of the evaporator wick of Figure 1;

Figure 3 is a side elevation of the left side of the evaporator wick of Figure 1;

Figure 4 is a side elevation of the right side of the evaporator wick of Figure 1; and

Figure 5 is a bottom view of the evaporator wick shown in Figure 1.

We claim:

The ornamental design for an evaporator wick, as shown.
